UNITED STATES PATENT OFFICE.

JEREMIAH WONDER, OF TRUCKSVILLE, ASSIGNOR TO HIMSELF AND
LORING A. ROBERTSON, OF DUNNING, PENNSYLVANIA.

IMPROVEMENT IN TANNING.

Specification forming part of Letters Patent No. 41,666, dated February 16, 1864.

To all whom it may concern:

Be it known that I, JEREMIAH WONDER, of Trucksville, in the county of Luzerne and State of Pennsylvania, have invented and applied to use a certain new and useful Improvement in Tanning; and I do hereby declare the following to be a full, clear, and exact description of the nature and object of the said invention and of the mode of applying the same to use.

The use of hemlock-bark in the operation of tanning produces a reddish color in the leather. This may be partially prevented by the use of oak-bark mixed to a large proportion with the hemlock. The leather tanned with oak-bark is much lighter in its color, and is generally preferred on that account to the hemlock-tanned leather, although, aside from the color, the leather itself is very nearly equal in quality, whether tanned by the one bark or the other.

The nature of my said invention consists in the addition to the tanning-matter of substances that will neutralize or partially neutralize the coloring-matter of the hemlock-bark, and thereby render the leather of a lighter or fairer color. For this purpose I employ bran, cracked or crushed oats, corn, wheat, or similar vegetable matter, which I apply in the tannats to the tanning-liquor; or I mix the same with the dry bark in the necessary proportion. If hemlock-bark alone is used, the proportion of this vegetable matter must be greater than

when oak and hemlock bark are mixed, and where cracked oats or grain is employed the proportion will require to be less than where bran is employed. Potatoes crushed or barley growth might be used. I have found that about two barrels of bran to an ordinary tannat of seven by nine feet and four feet deep will be about the correct proportion. When this vegetable matter has remained in the tanning-liquid for two or three days a visible change will have been effected, which will be apparent on tasting the liquid or examining its color. The leather tanned in this liquid will be found to be of a lighter and fairer color than it would have been had said vegetable matter not been employed, and the quality of the leather will not be injured thereby.

This improvement may be applied with hemlock-bark alone, or where any other tanning-matter is mixed with it.

What I claim, and desire to secure by Letters Patent, is—

The employment of the substances herein specified, in connection with hemlock-tan, for the purposes and as specified.

In witness whereof I have hereunto set my signature this 28th day of October, 1863.

JEREMIAH WONDER.
